ENDLESS TRACK WHEEL GUIDE LUG

Edouard Martin Comellas, 1410 Stanley St., Room 411,
Montreal, Quebec, Canada

Filed Sept. 13, 1968, Ser. No. 13,526

Term of patent 14 years

Int. Cl. D12—14

U.S. Cl. D14—30

FIG. 1 is a side elevational view of the endless track wheel guide lug embodying my new design.

FIG. 2 is a top plan view thereof.

FIG. 3 is a bottom plan view thereof.

FIG. 4 is an opposite side elevational view thereof.

FIG. 5 is a right end elevational view thereof.

FIG. 6 is a left end elevational view thereof.

FIG. 7 is a perspective view thereof.

I claim:

The ornamental design for an endless track wheel guide lug, as shown.
